(57) CLAIM

We claim the ornamental design for a server front cover set, as shown and described.

DESCRIPTION

FIG. 1 is a front right side perspective view of a server front cover set.

FIG. 2 is a front elevational view thereof.

FIG. 3 is a left side elevational view thereof.

FIG. 4 is a right side elevational view thereof.

FIG. 5 is a top plan view thereof.

FIG. 6 is a bottom plan view thereof.

FIG. 7 is a front top left side perspective view thereof; and, FIG. 8 is a front bottom left side perspective view thereof.

Any broken lines included in the figures, including any boundary created thereby, illustrate environmental matter only and do not form a part of the claimed design.
